UNITED STATES PATENT OFFICE.

ALVA A. LINDLEY, OF OSKALOOSA, IOWA.

TRACK-SANDING APPARATUS.

SPECIFICATION forming part of Letters Patent No. 608,881, dated August 9, 1898.

Application filed August 11, 1897. Serial No. 647,896. (No model.)

To all whom it may concern:

Be it known that I, ALVA A. LINDLEY, of Oskaloosa, in the county of Mahaska and State of Iowa, have invented a new and Improved 5 Track-Sanding Apparatus, of which the following is a full, clear, and exact description.

My invention relates to a track-sanding apparatus particularly designed for use in connection with locomotives, but applicable to 10 other motors where an air-blast may be obtained.

It consists of certain improvements connected to or formed as a part of the ordinary valve by which an air-blast may be used for 15 discharging the sand when desired without interfering with the ordinary manner of operating the valve.

Reference is to be had to the accompanying drawings, forming a part of this specification, 20 in which similar characters of reference indicate corresponding parts in all the views.

Figure 1 is a cross-sectional elevation of my valve, and Fig. 2 is a cross-sectional elevation taken upon the lines 6 6 of Fig. 1.

25 One object sought to be accomplished in my invention is to provide a pneumatic sanding device which will not interfere with the use of the valve as an ordinary valve—that is, to permit the discharge of sand by using the 30 valve in the ordinary manner and, in fact, to permit the use of the pneumatic device at the same time that the sand is discharged by moving the valve to uncover the discharge-opening in the ordinary manner.

35 The valve B is mounted upon the bottom of the sand-box A in the usual manner, which consists in a journal b projecting through the bottom of the box and attached to a crank-arm B', connected in any suitable manner, to 40 be operated from the cab of the engine. The valve B is, however, constructed in a manner differing somewhat from the ordinary valve. This valve is provided with a passage B², extending from the discharge-opening a in the 45 bottom of the sand-box toward the interior of the sand-box and connecting with the side-extending passages e'.

The air-blast connection is made through the journal b of the valve. This journal is

made hollow and is connected by a pipe D' 50 and hose D² with the air-supply. The passage d², connecting with the hollow journal, is curved, so as to join the passage B², leading to the discharge-opening. In the same valve a passage d' is shown leading to the top 55 of the valve, by which air-blast connection may be made to the top of the valve, if desired. One of these connections which is not in use will be closed by a plug, as shown.

The connection to the interior of the sand-box through which the sand is drawn is shown as consisting of the side passages e', leading from the inner end of the passages B² downward to the interior of the sand-box. These passages are protected by an overhanging 65 flange E², so that the sand will not work out therethrough when the air-blast is turned off. It will be seen that with the parts properly proportioned the valve may be moved to uncover a portion of the discharge-opening a 70 while the discharge-passage B² is in connection with the discharge-opening. This permits the pneumatic discharge to be used and supplemented at the same time by a slight discharge through the movement of the valve to 75 partially uncover the sand-discharge opening. This may be resorted to when it is desired to supplement the pneumatic discharge by using the valve in the ordinary manner.

When it is desired, the valve may be moved 80 even farther, so as to entirely uncover the discharge-opening a, and in this case the valve is used in the ordinary manner and the pneumatic discharge is entirely cut off.

It will thus be seen that my device may be 85 applied to present locomotives without in any way changing the same and in such a way that the valve may be operated in the ordinary manner whenever desired. The use of the pneumatic sanding device will result 90 in great economy in the use of the sand, at the same time permitting the liberal use thereof whenever needed.

Having thus described my invention, I claim as new and desire to secure by Letters 95 Patent—

A pneumatic sander for locomotives, comprising a valve pivoted upon the bottom and

within the sand-box, and adapted to cover the discharge-opening, a hollow journal on the valve, extending through the bottom of the sand - box and having air connections thereto, means connected to said journal for operating the valve, said valve having a passage therein connecting the discharge-open-

ing with the sand-box interior, and connections from the hollow journal into said passage, substantially as described.

ALVA A. LINDLEY.
